FIRE CONTROL FOR POWDER ACTUATED
TOOLSRobert T. Catlin, Stratford, Conn., assignor to
Remington Arms Company, Inc., Bridgeport,
Conn., a corporation of Delaware

Application October 24, 1951, Serial No. 252,949

1 Claim. (Cl. 1-44.5)

1

This invention relates to industrial tools of the type in which an element is forcefully driven against or into the work by gas pressure derived from the combustion of a propellant powder, and contemplates an improvement in such tools which requires that for operation the tool be held in a position substantially perpendicular to the face of the work.

More specifically, the invention contemplates an improvement in a tool of the type shown in the pending application for United States patent of Walker, Serial No. 225,146, filed May 8, 1951; said improvement providing that the firing mechanism remains locked even when the tool is pressed against the work surface unless the tool is substantially perpendicular to such surface.

In the drawings:

Fig. 1 is a longitudinal sectional view of a complete tool embodying the present invention.

Fig. 2 is a line diagram illustrating the fact that the sear remains locked when the tool is pressed against the work surface in a position inclined to the work surface.

Fig. 3 is a fragmentary longitudinal section showing the sear unlocked by the pressure of the tool against the work surface in a position substantially perpendicular thereto.

Figure 4 is a fragmentary sectional view of a modification.

The illustrative tool shown in the drawing comprises a barrel 1 provided with a chamber 2 adapted to receive a cartridge which is provided with a projectile in the form of a stud or other element to be driven into or against the work. The chamber is closed by a breech block 3 which is apertured to provide for the movement of a firing pin 4 to engage the cartridge primer. Breech block 3 is secured in a frame 5 which houses the firing mechanism and is extended into a handle or grip 6. The firing pin 4 is provided with a sear-engaging enlargement 7 and is urged forwardly by a firing spring 8. Cooperating with the sear-engaging part 7 is a sear 9 pivoted in the frame at 10 and provided with a head 11 adapted for displacement to release the firing pin by cam engagement with a trigger 12 which is mounted for rectilinear movement in the frame and is provided with a finger piece 13 within the grip 6. Normally the sear is locked against firing pin releasing movement by a sear lock 14 which underlies the firing pin engaging portion 9 of the sear and is mounted for rectilinear movement in the frame, being thrust forward to its effective or sear-locking position by a spring 15 (Fig. 1).

The barrel is held in a housing 16 provided with an end plate 17 to which the barrel is secured, said end plate being rotatably secured to the breech block 3 by means of the pivot stud 18.

2

Slidably mounted on the barrel 1 within the housing 16 is an action tube 19 to which is secured an action bar 20 that extends rearwardly in alignment with and is adapted to displace the sear lock 14, to permit firing. Secured to the forward end of the action tube 19 and extending forwardly therefrom through housing 16 is an action tube extension 21. A spring 22 interposed between the rear end of the action tube extension 21 and a shoulder on the barrel normally holds the action tube assembly 19-20-21 in the forward position illustrated in Fig. 1.

The tool as thus far described is substantially identical with the one shown in the aforementioned application of Walker, and is designed particularly for driving studs into difficultly penetrable materials, such as cinder block, cement block, Portland cement concrete, and steel. The impact of the stud against aggregate materials of the concrete type tends to dislodge and forcefully expel small fragments or chips at the surface. To prevent damage and injury by such flying particles, it is desirable to provide a shield which must be firmly pressed against surface of the wall, floor, beam or other structural member or fixture which is to be penetrated by the driven stud. For convenience, in this specification and the claim appended thereto, any member to which the tool is applied for the purpose of securing a stud therein will, in accordance with well-established practice, be referred to as the "work." Since the work is usually a hard and difficultly penetrable material it becomes important to insure that the tool be so applied to the work surface that the stud is driven in a direction substantially perpendicular to said surface, rather than oblique thereto. The present invention provides not only that the tool must be held against the work, but that it must be held essentially perpendicular to the work surface to enable firing movement of the sear.

To this end, two assemblies are provided, one an action tube assembly or "action member" comprising action bar 20, action tube 19 and action tube extension 21; and the other a guard assembly slidably mounted on the reduced portion 21 of action tube extension 21 and comprising guard 25 having a collar 24 fixed to the sleeve 23. Within the conical body of guard 25 and terminating in a face substantially perpendicular to the axis of the action tube and the barrel is a body 26 of a yieldably resilient material such as rubber or NEOPRENE. The sleeve 23 of the guard assembly terminates in a shoulder 231 which is wider than the shoulder 212 and is thus adapted for engagement with the end face 161 of housing 16 (Fig. 3). The action tube assembly (comprising parts 19, 20 and 21) being extended, the guard

assembly (comprising ports 23, 24 and 25) thus has a movement upon action tube extension 21 equal to the difference between the length of the sleeve 23 and the spacing between collar 213 and shoulder 212.

It will be remembered that the purpose of the tool is to fire a cartridge which is placed in chamber 2, thereby driving a projectile into a surface which is engaged by the guard 25; that projectile firing is effected by movement of the firing pin 4 which is held in cocked position against the compression of spring 8 by sear 9; that firing pin releasing movement of said sear 9 is normally blocked by sear lock 14; and that sear lock 14 is displaced to permit movement of sear 9 by action bar 20. The mechanism constituting the present invention is designed to insure that the sear lock 14 is not displaced to permit firing unless the tool is held substantially perpendicular to the work face, as illustrated in Fig. 3. The end of action bar 20 is normally some distance away from the sear lock, as seen in Fig. 1. If the tool is held oblique to the work face, in some such position as illustrated in Fig. 2, the rearward movement of action bar 20 is inadequate to engage and displace the sear lock, as clearly illustrated in Fig. 2. This is by reason of the fact that the action member (which comprises action tube 19, action bar 20 and action tube extension 21, all rigidly secured together and moving as a unit), has not performed its full rearward movement with respect to the barrel.

Fig. 1 shows the guard assembly in an intermediate position on the action tube extension 21, on which it floats between shoulders 212 and 213, the action member, including the action tube extension, being thrust forwardly with respect to the barrel by spring 22. If the tool is presented obliquely to a work surface, a portion of the rim of guard 25 engages such work surface, thrusting the guard rearwardly on the action tube extension until the guard shoulder 231 engages the action tube extension shoulder 212. Thereafter, guard and action tube extension move rearwardly with respect to the barrel until the guard shoulder 231 engages the forward end 161 of barrel housing 16, as shown in Fig. 2, stopping further rearward movement. The action member, being thrust forwardly on the barrel by spring 22 and the guard being pushed to the rearward limit of its movement on the action member, the action member protrudes from the work engaging face of the guard, and action bar 20 has not engaged sear lock 14. In this non-functioning position, it is obvious that the tool cannot be fired. If now the tool, being continuously thrust toward the work surface, is swung into a position substantially perpendicular to the work surface, as shown in Fig. 3, the guard assembly (comprising ports 23, 24 and 25) remains in the same position with respect to the barrel and its housing, due to the engagement of guard shoulder 231 with barrel housing shoulder 161, but the action member (comprising ports 19, 20 and 21) moves rearwardly with respect to both barrel and guard and in this movement the end of action bar 20 engages and displaces sear lock 14, as clearly shown at the right end of Fig. 3, thus enabling the tool to be fired. Any desired variation from the perpendicular within which firing can be done may be provided merely by varying the over-all length of the action tube assembly.

Fig. 4 shows a modified construction in which the guard collar 24 is floated directly upon the action tube extension 21. A stud 30 projecting

outwardly from the action tube is received in a counterbore 31 in a sleeve member 32, which is secured to the guard collar 24 and floats on the action tube extension 21. The action tube extension 21 being forward, motion of the guard assembly thereon is limited by the engagement of stud 30 with the end of collar 24 and the end 321 of counterbore 31. When the tool is pressed against a work surface, the rearward movement of the guard assembly (comprising ports 25 and 32) is limited by the engagement of the end 322 of sleeve 32 with the end 161 of housing 16 or a ring 33 of a buffer material such as NEOPRENE placed thereon. The construction of this modification is otherwise identical with that shown in Fig. 1; particularly in that within the housing 16, action tube extension 21 is joined to an action tube 19 which in turn is connected to action bar 20. Only when action bar 20 is fully displaced to the rear can it engage and displace sear lock 14, to permit firing; and this occurs only when the guard is against the frame 16, and the end of the action tube extension is flush with the guard face. If the tool is thrust obliquely against the work surface, only a small portion of the rim of guard 25 engages such surface and, due to this engagement, the guard is thrust rearward until shoulder 322 thereon engages the end 161 of the housing 16, preventing further rearward movement of guard and action assembly. In this non-functioning condition, the forward end of action tube extension 21 protrudes from the work engaging face of the guard and the sear remains locked. As the tool is swung to a position perpendicular to the work face the action tube extension is moved rearwardly within the guard and the barrel housing until its free end is substantially flush with the work engaging face of the guard, thereby unlocking the action. This and other modifications are within the purview of the invention and the scope of the appended claim.

What is claimed is:

In a powder actuated tool adapted to drive a fastener into relatively fixed work, a barrel assembly comprising a barrel housing and a barrel having a rearward breech end housed in said housing, extending forwardly through and projecting from said housing and terminating in a muzzle plane perpendicular to the axis of said barrel; a frame assembly joined to said barrel assembly and comprising a firing device, a sear for controlling said firing device and a lock for said sear; a unitary action assembly comprising a tubular member mounted for longitudinal movement on said barrel from a forward normal position in which its forward end is in front of said muzzle plane to a rearward fully displaced position in which its forward end is substantially at said muzzle plane; a guard assembly mounted for limited movement on said tubular member and comprising a work-engaging face substantially perpendicular to the axis of said barrel, said guard assembly comprising motion limiting means adapted to engage said frame when the work-engaging face of the guard assembly is in the muzzle plane; said action assembly further comprising an action bar adapted to engage and displace said sear lock as said action assembly approaches its fully displaced position and the work-engaging face of the guard assembly is in the muzzle plane.
